UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed June 5, 1919, Serial No. 301,917. Renewed May 11, 1927.

My invention relates to mining machines. It has among its objects to provide an improved mining machine having an improved and simplified feeding mechanism. 5 A further object of my invention is to provide an improved flexibly fed mining machine having an improved arrangement of its flexible feeding mechanism and improved operative connections for actuating said 10 mechanism to propel the machine. Another object of my invention is to provide an improved flexibly fed machine of the so-called longwall type. A still further object of my invention is to provide an improved 15 and simplified feeding arrangement and mechanism for a chain propelled mining machine, and more especially for a chain propelled mining machine of the longwall type whereby the same is rendered better 20 adapted to service conditions. These and other objects and advantages of my improved construction will, however, herein-after more fully appear.

In the accompanying drawings, I have 25 shown for purposes of illustration two embodiments which my invention may assume in practice.

In these drawings,

Fig. 1 is a plan view of one form of my 30 invention, the rear end of the casing being broken away and the feed mechanism being shown partially in section.

Fig. 2 is an end elevation of the machine shown in Fig. 1 illustrating the improved 35 arrangement of the chain driving and guide sprockets.

Fig. 3 is a plan view showing the machine in operation when cutting in one direction, with the chain also shown in dotted lines in 40 its transport arrangement.

Fig. 4 is a similar view showing the machine cutting in the opposite direction with the chain also shown in dotted lines in its cutter bar swinging arrangement.

Fig. 5 is a plan view similar to that shown 45 in Fig. 1, showing a modified construction of a portion of the feeding mechanism.

In the illustrative construction shown in Figs. 1 to 4, I have shown a longwall machine including a usual elongated machine frame 1 mounted on a shoe 2 and slidable thereon over the mine bottom in planes adjacent the latter, the frame carrying a suitable motor 3, herein of the usual reversible 50 type and horizontally and longitudinally

disposed and as usual centrally located between the feed driving mechanism and the cutter chain driving mechanism. Inasmuch as the latter mechanism does not enter into the present invention, it will therefore herein suffice to say that the same includes a cutter bar 4 pivotally mounted on one end of the frame 1, the bar carrying the usual cutter chain 5 driven from one end of the motor shaft through usual mechanism not shown, and being movable angularly into a plurality of positions about its pivot and adapted to be fixed in any position by suitable pins 6, all in a well known manner.

In my improved construction, it will be 70 observed that a feed operating member, herein in the form of a driving sprocket 7 for cooperating with the feed chain 8, is disposed in an improved manner on a horizontal axis at the opposite end of the frame 75 from the cutter bar, which in a longwall machine is the front of the machine frame, and driven by improved mechanism. As shown in this form of my invention, this driving sprocket 7 is disposed transversely 80 of the front of the frame and rotatable in a vertical plane about a longitudinally disposed axis located in the center of the machine. As shown, it is also driven from the motor, the adjacent end of the motor armature shaft 9 carrying a worm 10, which in turn meshes with a worm gear 11 centrally fixed to a transversely disposed cooperating horizontal sprocket driving shaft 12, in turn journaled in suitable bearings 90 13 on opposite sides and the bottom of the frame. As illustrated, this shaft 12 is herein connected to the sprocket 7 through a plurality of improved operative connections or trains of gearing whereby this sprocket 95 may be rotated in opposite directions at a plurality of speeds, and improved controlling mechanism is also herein provided whereby the feed may be reversed whatever its direction, without reversing the motor.

Referring to the feed driving mechanism, we will first consider the slow feed mechanism. Herein it will be observed that a small pinion 14 is fixed near one end of the shaft 12 and meshes with a larger pinion 15 carried on the inner end of a stub shaft 16 journaled on the frame and disposed parallel to the shaft 12 and between the latter and the motor. This stub shaft 16 in turn carries a small pinion 17 on its opposite end,

which meshes with a larger pinion 18 freely rotatable on the shaft 12 and disposed between the pinion 14 and the side of the frame. As shown, this pinion 18 in turn meshes with a still larger pinion or gear 19, which is suitably connectible with a rearwardly located transversely disposed shaft 20 by means of a friction clutch mechanism 21 including the usual fixed and movable elements, herein of the disc type, and controlled by a usual clutch shipper 22 movable on the shaft 20 and herein operable by controlling mechanism including a lower lever 23 engageable with the shipper and 15 operatively connected through a transverse link 24 and other mechanism not shown, with a controlling lever 25 disposed on the top of the machine casing. As shown, a bevel gear 26, freely rotatable on the shaft 20, constantly meshes with a larger bevel gear 27 on one end of a short longitudinally and horizontally disposed, centrally located shaft 28 suitably journaled in the frame and carrying the feed driving sprocket 7 on its 25 opposite end. In the fast feed mechanism, it will be noted that fixed to the opposite end of the shaft 12 from the pinion 14, is a suitable small pinion 29 meshing with a considerably larger gear 30 rotatable on the 30 opposite end of the shaft 20 from that carrying the gear 19 and similarly located. The connection of this gear 30 to the shaft 20 is in turn controlled by a suitable friction mechanism 31 similar to the friction mechanism 21, and likewise controlled by a shipper 32 through a lever 33, the lever in turn being connected to the link 24 and likewise controllable by the controlling lever 25 located on the top of the casing. Here it will 35 be observed that a freely rotatable bevel gear 34 similar to the gear 26 and likewise constantly meshing with the gear 27 is also provided. Thus, it will be observed that when the lever 25 is operated in such a manner as to operate the clutch shipper 22 in one direction, the clutch 31 is disconnected and the clutch 21 is caused to connect the slow feed mechanism, including the gears 14, 15, 17, 18, 19, 26, and 27, to the shaft 28, while 40 when this controlling lever 25 is operated in such a manner as to actuate the shipper 32 to connect the clutch 31, the clutch 21 is disconnected and the feed is connected through the fast feed mechanism, including 45 the gears 29, 30, 34 and 27, to the shaft 28. 50 In my improved construction, it will also be observed that I have provided upon the shaft 20 and between the bevel gears 26, 34, which mesh constantly with the larger bevel gear 27, improved controlling mechanism 55 for controlling the rotation of the feed sprocket driving shaft 28. Herein, this mechanism assumes the form of a clutch member 35 splined to the shaft 20 between the bevels and having suitable teeth 36, 37

on its opposite ends adapted to engage with corresponding teeth formed on the bevel gears 26, 34 when the shipper is actuated through a lever 38 from a controlling lever 39 (Figs. 3 and 4) operable from the top of the casing. As a result of the provision of this mechanism, it will be observed that while the lever 25 may be operated alternately to connect the feed sprocket with either the fast or slow feed mechanism and thereby rotate the feed sprocket in opposite directions at different speeds, as desired, it is also possible by manipulation of the lever 39 to reverse either the fast or slow feed, as desired, and thereby obtain a fast or slow feed in either direction.

To cooperate with my improved feed operating member or sprocket, I preferably provide on opposite sides of the same, and herein beneath the same, cooperating guiding sprockets 40 and 41, all three sprockets preferably being disposed in the same vertical plane and transversely across the front end of the machine frame and above a horizontal plate 42 thereon. Here it will also be observed that I have provided further cooperating guide sprockets 43, 44, and 45, rotatable on vertical axes and disposed in a horizontal plane on this plate 42 and beneath the sprockets 40 and 41, the sprocket 44 being preferably disposed slightly in front of its fellows and in the center line of the machine, while the sprockets 43 and 45 are so disposed at the corners of the end of the frame and preferably extended laterally slightly beyond the lines thereof as to permit the chain to be passed around either side thereof. By this improved arrangement of the feed sprocket and its cooperating guiding elements, it will be observed that it is possible to shorten the machine materially and to simplify the driving connections. It is also made possible when desired to apply the feed chain with great facility, it only being necessary to grasp the same at any loose point or bight and throw the same over the feed sprocket, whereupon by starting the feed the chain is caused to assume its operative relation with respect to the guide sprockets 40 and 41, all necessity for so called "threading" the feed chain being thereby avoided. It will also be observed that through my improved arrangement, wherein the feed sprocket rotates in a vertical plane, all liability of separation of the feed chain from the feed sprocket during slack conditions of the chain, is thereby eliminated, the weight of the chain holding it in operative relation to its sprocket.

In considering the use of my improved construction, reference is made to Figs. 3 and 4. In Fig. 3, it will be observed that I have shown the chain when in one position by the usual dash and dot chain line, this position being the usual operating position

of the chain during cutting wherein it extends from its free end under the guide 41, over the chain driving sprocket 7, and under the guide 40, and is then extended around the corner sprocket 43 to a fixed point in advance of the machine, as for instance a jack 46 adjacent the face. In this figure, it will be observed that I have also shown the chain in dotted lines in its transport position, i. e. the position which the same occupies when the bar is also in the dotted transport position shown and the machine is ready for transport. In this position, it will be observed that the chain is reversely disposed and extends from its free end down under the sprocket 40, over the chain driving sprocket 7, under the sprocket 41, around the sprocket 45, and back around the sprocket 44 to a point directly in front of the center line of the machine. Considering Fig. 4, it will be observed that therein I have similarly illustrated the chain in the usual dash and dot chain line as connected to propel the machine during cutting in the opposite direction from that shown in Fig. 3, the chain then being extended from its free end under the guide 40, over the chain driving sprocket 7, under the guide 41 around the sprocket 45, and forward to the jack 46. In this figure, it will be observed that I have also illustrated in dotted lines the position of the chain when disposed in my improved arrangement for swinging the bar 4 from its cutting position out of the coal, or, similarly, from the transport position (shown in Fig. 3) into the coal when cutting an oppositely located face. In this position, it will be observed that the same arrangement relative to the sprocket 7, and guides 40 and 41, obtains, but that in this instance the chain, instead of being passed forward by the sprocket 45, is again passed laterally across the frame and in front of the sprockets 44 and 43, and then brought rearward around the rear end of the machine and connected to the swing hook 47 on the bar. Obviously this arrangement of the feed chain may be reversed to swing the bar under the face or withdraw the same from the face when the machine is reversely disposed relative to the face. It will also be understood that during the cutting operations, i. e. when the bar is being swung in under the face or when the machine and bar are both moving bodily along the face, the feed operating member 7 is driven at a slow or cutting speed in the desired direction determined by the adjustment of the controlling mechanism, while when the machine is being transported or the bar is being swung when not cutting the member 7 is rotated at the fast speed with its direction similarly controlled. Attention is here also directed to the fact that whatever the speed or direction of the feed operating member a reverse feed

may be obtained by reversing the arrangement of the feed chain. It will also be understood that through the provision of the reversible driving connections for the feed operating member 7 the latter is also reversely operable to reverse the feed without changing the feed chain while the feed may also be reversed by reversing the motor. It will also be observed that since the member 7 may be reversely driven without reversing the motor the cutter chain 5 may be reversely driven at any time, as shown in Figs. 1 and 3 for example, without affecting the feeding of the machine which may be effected at fast or slow speed in either direction while the cutter chain is being rotated in either direction.

In Fig. 5, I have illustrated a partially modified form of feed driving mechanism and a modified arrangement of the chain driving and guiding sprockets. In this construction, it will be observed that instead of using the bevel gear reverse drive described in connection with Fig. 1, a vertically disposed spur gear 48 is provided midway between the ends of the frictions 21 and 31 on the shaft 20. This spur gear meshes with a larger gear 49, in turn carried directly on a horizontal shaft 50 carrying a plurality of feed sprockets 51, herein on its opposite ends. This shaft 50 is herein transversely disposed and journaled in suitable bearings 52 formed on the frame. As shown, it is also short and set midway between the sides of the frame, suitable pockets 53 being provided at its opposite ends so that the chain driving sprockets 51 may be housed within the lines of the frame. Associated with these driving sprockets, either of which may be used when desired, I have also provided supplementary guide sprockets 54, 55 rotatable on vertical axes and adapted to direct the chain from the chain driving sprockets 51 to slightly forwardly located laterally disposed cooperating guide sprockets 56, 57 rotatable on vertical axes and corresponding to the guides 43, 45 or a pair of forwardly located cooperating guide sprockets 58 having the plane of their axes disposed parallel to the plane of the axes of the members 56, 57. In this construction, it will be evident that by simply laying the chain around either of the guides 54 or 55 and over either of the chain driving sprockets 51, and passing the same around the front guide sprockets 58 and either of the guides 56, 57, as shown in dash and dot chain lines in this figure, the machine may be connected for movement along the face, and that by similar rearrangements of the chain to that described above in connection with the form of my invention shown in Figs. 1, 2, 3, and 4, various other movements of the machine or its bar may be obtained, as desired.

As a result of my improved construction,

it will be observed that it is possible to eliminate entirely any necessity for threading the chain, thereby facilitating and speeding up the use of the machine under service conditions, at the same time that it is possible to utilize the weight or the slack chain to hold it upon the feed sprocket and to locate the chain driving mechanism as to interfere in no way with the movement of the machine close to the face on the one hand and the props on the other. Attention is also directed to the fact that due to my improved disposition of the feed operating member and more particularly to its disposition on an axis extending longitudinally of the machine frame, it is made possible when desired to produce a very compact construction longitudinally, all necessity for increasing the length of the machine by the diameter of the feed operating member being eliminated. In practice, I further find that this arrangement of the feed operating member is also very advantageous in that it lends itself readily to simplified forms of driving mechanism and also to mechanism readily accessible from the end of the machine. Further, by the elevation of the feed operating axis, the difficulty with slack is eliminated at the same time that, due to the horizontal disposition of the bearings, lubrication is facilitated, especially as compared with feed operating members on a vertical axis. It will also be observed that through my improved feed sprocket driving and control mechanism it is possible to reduce the gearing ordinarily required in this type of machine and enable greater flexibility of control to be obtained, either speed feed being capable of being reversed when desired without reversing the motor. These and other advantages of my improved construction will, however, be clearly apparent to those skilled in the art.

While I have in this application specifically described two embodiments which my invention may assume in practice, it is to be understood that these forms are used for purposes of illustration, and that the invention may be further modified and embodied in various other forms without departing from its spirit or the scope of the appended claims.

What I claim as new and desire to secure by Letters Patent is:

1. The combination with a mining machine frame having a cutter bar projecting from one end thereof, of feeding means including a flexible feeding portion adapted during feeding to cooperate with a fixed point outside the machine frame, and means on said frame cooperating with said flexible feeding portion including a motor and a feed operating member driven thereby and operatively engaging said flexible portion and rotatable on an axis extending longitudinally of the machine frame on the opposite end of said frame from said cutter bar to effect movement of said machine to extend its cut in the direction of said fixed point.

2. The combination with a mining machine frame having a cutter bar projecting from one end thereof, of feeding means including a flexible feeding portion adapted during feeding to cooperate with a fixed point outside the machine frame, and means on said frame cooperating with said flexible feeding portion including a motor and a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and a cooperating guiding means on a parallel axis.

3. The combination with a mining machine frame having a cutter bar projecting from one end thereof, of feeding means including a flexible feeding portion adapted during feeding to cooperate with a fixed point outside the machine frame, and means on said frame cooperating with said flexible feeding portion including a motor and a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and a plurality of cooperating guiding means each disposed on a parallel axis.

4. The combination with a mining machine frame having a cutter bar projecting from one end thereof, of feeding means including a flexible feeding portion adapted during feeding to cooperate with a fixed point outside the machine frame, and means on said frame cooperating with said flexible feeding portion including a motor, a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and a cooperating guiding means disposed on an intersecting axis.

5. The combination with a mining machine frame having a cutter bar projecting from one end thereof, of feeding means including a flexible feeding portion adapted during feeding to cooperate with a fixed point outside the machine frame, and means on said frame cooperating with said flexible feeding portion including a motor, a feed operating member driven thereby and operatively engaging said flexible portion and

rotatable on an axis extending longitudinally of the machine frame on the opposite end of said frame from said cutter bar to effect movement of said machine to extend its cut in the direction of said fixed point, and a plurality of cooperating guiding means each disposed on an axis parallel to a line intersecting said longitudinal axis.

6. The combination with a mining machine frame having a cutter bar projecting from one end thereof, of feeding means including a flexible feeding portion adapted during feeding to cooperate with a fixed point outside the machine frame, and means on said frame cooperating with said flexible feeding portion including a motor, a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and a plurality of cooperating guiding means arranged on mutually parallel axes one of which last mentioned axes intersects the longitudinal axis.

7. The combination with a mining machine frame having a cutter bar projecting from one end thereof, of feeding means including a flexible feeding portion adapted during feeding to cooperate with a fixed point outside the machine frame, and means on said frame cooperating with said flexible feeding portion including a motor, a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and cooperating guiding means disposed on a vertical axis.

8. The combination with a mining machine having a cutter bar projecting from one end thereof, of feeding means including a flexible feeding portion adapted during feeding to cooperate with a fixed point outside the machine frame, and means on said frame cooperating with said flexible feeding portion including a motor, a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and a plurality of cooperating guiding means each disposed on a vertical axis.

9. The combination with a mining machine having a cutter bar projecting from one end thereof, of feeding means including a flexible feeding portion adapted dur-

ing feeding to cooperate with a fixed point outside the machine frame, and means on said frame cooperating with said flexible feeding portion including a motor, a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and a plurality of cooperating guiding means each disposed on a vertical axis, one of which last mentioned vertical axes is disposed perpendicular to said longitudinal axis.

10. The combination with a mining machine having a cutter bar projecting from one end thereof, of feeding means including a flexible feeding portion adapted during feeding to cooperate with a fixed point outside the machine frame, and means on said frame cooperating with said flexible feeding portion including a motor, a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and cooperating guiding means on parallel and intersecting axes.

11. The combination with a mining machine having a cutter bar projecting from one end thereof, of feeding means including a flexible feeding portion adapted during feeding to cooperate with a fixed point outside the machine frame, and means on said frame cooperating with said flexible feeding portion including a motor, a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and cooperating guiding means on parallel and on vertical axes.

12. The combination with a mining machine having a cutter bar projecting from one end thereof, of feeding means including a flexible feeding portion adapted during feeding to cooperate with a fixed point outside the machine frame, and means on said frame cooperating with said flexible feeding portion including a motor, a feed operating member driven thereby and operatively engaging said flexible portion and rotatable on an axis extending longitudinally of the machine frame on the opposite end of said frame from said cutter bar to effect movement of said machine to extend its cut in the direction of said fixed point, and cooperating guiding means including guiding means

whose axis of rotation is parallel to said longitudinal axis and guiding means whose axes of rotation respectively intersect said longitudinal axis and are parallel to the axis which intersects said longitudinal axis.

13. The combination with a mining machine frame having a cutter bar projecting from one end thereof, of feeding means on said frame including a motor, and a feed operating member driven thereby and rotatable on the opposite end of said frame on an axis extending longitudinally of the machine frame and adapted to cooperate directly with a flexible feeding member, and co-operating guiding means rotatable on parallel and on vertical axes, the guiding means rotatable on vertical axes being disposed at the corners of said frame.

14. The combination with a mining machine frame having a cutter bar projecting from one end thereof, of feeding means on said frame including a motor, and a feed operating member driven thereby and rotatable on the opposite end of said frame on an axis extending longitudinally of the machine frame and adapted to cooperate directly with a flexible feeding member, and co-operating guiding means rotatable on parallel and on vertical axes, the guiding means rotatable on vertical axes being disposed at the corners of said frame and at a point between said corners.

15. The combination with a mining machine frame having a cutter bar projecting from one end thereof, of feeding means on said frame including a motor, and a feed operating member driven thereby and rotatable on the opposite end of said frame on an axis extending longitudinally of the machine frame and adapted to cooperate directly with a flexible feeding member, and co-operating guiding means rotatable on axes parallel to said longitudinal axis and on mutually parallel axes parallel to a line intersecting said longitudinal axis, the last mentioned guiding means being disposed at corners of the frame.

16. The combination with a mining machine frame having a cutter bar projecting from one end thereof, of feeding means on said frame including a motor, and a feed operating member driven thereby and rotatable on the opposite end of said frame on an axis extending longitudinally of the machine frame and adapted to cooperate directly with a flexible feeding member, and co-operating guiding means rotatable on axes parallel to said longitudinal axis and on mutually parallel axes parallel to a line intersecting said longitudinal axis, the last mentioned guiding means including guiding means disposed at corners of said frame and guiding means rotatable upon an axis intersecting said longitudinal axis.

17. The combination with a mining ma-

chine having a pivoted cutter bar, of feeding means therefor including a flexible feeding portion, and a feed operating member operatively engaging said flexible portion and rotatable on an axis extending longitudinally of the machine.

18. The combination with a mining machine having a cutter bar pivoted on its rear end, of feeding means therefor including a flexible feeding portion, and a feed operating member operatively engaging said flexible portion and rotatable on an axis extending longitudinally of the machine on the front end of said machine.

19. The combination with a mining machine having a pivoted cutter bar, of feeding means therefor including a flexible feeding portion, and a feed operating member operatively engaging said flexible portion and rotatable on an axis extending longitudinally of the machine on said machine and disposed on the opposite end of said machine from said bar.

20. The combination with a mining machine having a cutter bar pivoted on its rear end, of feeding means therefor including a flexible feeding portion, and a feed operating member operatively engaging said flexible portion and rotatable on an axis extending longitudinally of the machine on the front end of said machine and disposed within the lateral limits thereof.

21. The combination with a mining machine having a cutter bar pivoted on its rear end, of feeding means therefor including a flexible feeding portion, a feed operating member operatively engaging said flexible portion and rotatable on an axis extending longitudinally of the machine on the front end of said machine, and cooperating guiding means therefor.

22. The combination with a mining machine having a cutter bar pivoted on its rear end, of feeding means therefor including a flexible feeding portion, a feed operating member operatively engaging said flexible portion and rotatable on an axis extending longitudinally of the machine on the front end of said machine, and a plurality of cooperating guiding means therefor.

23. The combination with a mining machine having a cutter bar pivoted on its rear end, of feeding means therefor including a flexible feeding portion, a feed operating member operatively engaging said flexible portion and rotatable on an axis extending longitudinally of the machine on the front end of said machine, and a plurality of cooperating guiding means therefor disposed on vertical axes.

24. The combination with a mining machine having horizontal kerf cutting mechanism projecting therefrom at its rear end, of a feed driving member at the front end of said machine rotatable on a horizontal

axis, a flexible feed member cooperating with said feed driving member, and cooperating guiding means therefor engageable thereby before and after engagement with said driving member.

25. The combination with a mining machine having horizontal kerf cutting mechanism projecting therefrom at its rear end, of a chain driving sprocket at the front end 10 of said machine rotatable on a horizontal axis, a flexible feed chain cooperating with said feed driving member, and cooperating guiding means therefor engageable thereby before and after engagement with said 15 sprocket.

26. The combination with a longwall mining machine having horizontal kerf cutting mechanism projecting therefrom at its rear end, of a feed driving member at the front 20 end of said machine rotatable on a horizontal axis, a flexible feed member cooperating with said feed driving member, and cooperating guiding means therefor for directing said feed member around said driving member and forwardly from the front end of 25 said machine.

27. The combination with a mining machine, of a feed driving member at its front end rotatable on an axis extending longitudinally of the machine, a flexible feed member cooperating with said feed driving member, and cooperating guiding means for directing said feed member around said driving member and rearwardly from the 30 front end of said machine.

28. The combination with a longwall mining machine having horizontal kerf cutting mechanism projecting therefrom at its rear end, of a feed driving member at the front 35 end of said machine rotatable on a horizontal axis, a flexible feed member cooperating with said feed driving member, and cooperating guiding means therefor for directing said feed member around said driving member and either forwardly or rearwardly 40 from the front end of said machine.

29. The combination with a longwall mining machine, of a feed driving member at its front end rotatable on an axis extending 50 longitudinally of the machine, a flexible feed member cooperating with said feed driving member, and cooperating guiding means for directing said feed member around said driving member and laterally across the 55 front end of the machine.

30. The combination with a mining machine having horizontal kerf cutting mechanism projecting therefrom at its rear end, of a feed driving member at the front end 60 of said machine rotatable on a horizontal axis, a flexible feed member cooperating with said feed driving member, and cooperating guiding means therefor for directing said feed member around said driving mem-

ber and laterally in opposite directions 65 across the front end of the machine.

31. The combination with a mining machine having a pivoted cutter bar, of a feed driving member at its front end rotatable on an axis extending longitudinally of the machine, a flexible feed member cooperating directly with said feed operating member, and cooperating guiding means for directing said feed member around said driving member and laterally and longitudinally relative to said machine. 70 75

32. The combination with a mining machine having a pivoted cutter bar, of a feed driving member at its front end rotatable on an axis extending longitudinally of the machine, a flexible feed member cooperating directly with said feed operating member, and cooperating guiding means for directing said feed member around said driving member and laterally and longitudinally relative thereto at either side of said machine. 80 85

33. The combination with a mining machine having horizontal-kerf cutting mechanism projecting therefrom at its rear end, of a feed driving member at the front end of 90 said machine disposed on a horizontal axis, a flexible feed member engageable therewith, and guiding means including a plurality of simultaneously operative cooperating guiding members disposed on opposite sides of 95 said driving member and located in the same plane therewith.

34. The combination in a mining machine having horizontal-kerf cutting mechanism at the rear end thereof, of a feed driving member at the front end of the machine disposed on a horizontal axis, a flexible feed member engageable therewith, and guiding means including a plurality of simultaneously operative cooperating guiding members disposed on opposite sides of said driving member and so located that a single plane perpendicular to the axis of said feed driving member will cut each of them. 100 105 110

35. The combination in a mining machine having horizontal-kerf cutting mechanism at the rear end thereof, of a feed driving member at the front end of the machine disposed on a horizontal axis, a flexible feed member engageable therewith, and guiding means including a plurality of simultaneously operative cooperating guiding members disposed on opposite sides of said driving member and so located that the portion 115 120 of said flexible feed member engaging them and said feed driving member will lie in a single plane.

36. The combination with a mining machine, of a feed driving member disposed on a longitudinal axis at the front end thereof, a flexible feed member engageable therewith, and guiding means including a plurality of 125 cooperating guiding members disposed on

opposite sides of said driving member and located therewith in a transverse plane.

37. The combination with a mining machine, of a feed driving member disposed on a horizontal axis extending longitudinally of the machine at the front end thereof, a flexible feed member engageable therewith, a cooperating guiding member disposed adjacent said driving member, and a second cooperating guiding member simultaneously operative with said first mentioned cooperating guiding member and disposed on a vertical axis and located at one side of said machine.

38. The combination with a mining machine, of a feed driving member disposed on a horizontal axis at the front end thereof, a flexible feed member engageable therewith, a cooperating guiding member disposed adjacent said driving member, and a plurality of cooperating guiding members disposed on vertical axes and located on opposite sides of the axis of said driving member and in front thereof.

39. The combination with a mining machine, of a feed driving member disposed on a horizontal axis extending longitudinally of the machine at the front end thereof, a flexible feed member engageable therewith, a cooperating guiding member disposed adjacent said driving member, and a plurality of cooperating guiding members disposed on vertical axes and located on opposite sides of said driving member and in front thereof.

40. The combination with a mining machine, of a feed driving member disposed on a horizontal axis at the front end thereof, a flexible feed member engageable therewith, a cooperating guiding member on a horizontal axis, and a plurality of forwardly located cooperating guiding members disposed on vertical axes, one disposed at one side of said driving member and the other substantially in front thereof.

41. The combination with a mining machine, of a feed driving member disposed on a horizontal axis at the front end thereof, a flexible feed member engageable therewith, a plurality of cooperating guiding members on horizontal axes, and a plurality of cooperating guiding members disposed on vertical axes and located on opposite sides of said driving member and in front thereof.

42. The combination with a mining machine, of a feed driving member disposed on a horizontal axis at the front end thereof, a flexible feed member engageable therewith, a plurality of cooperating guiding members on horizontal axes, and a plurality of cooperating guiding members disposed on vertical axes, two on opposite sides of said driving member and one directly in front thereof.

43. The combination with a mining machine, of a feed driving sprocket disposed

on a horizontal axis extending longitudinally of the machine and rotatable in a transverse plane at the front end of the machine, a flexible feed chain engageable with said sprocket, and cooperating guiding means disposed in the same plane as said sprocket and located on opposite sides of the same.

44. The combination with a mining machine, of a feed driving sprocket disposed on a horizontal axis extending longitudinally of the machine and rotatable in a transverse plane at the front end of the machine, a flexible feed chain, and cooperating guiding means disposed in the same plane as said sprocket and located on opposite sides thereof and blow the same.

45. The combination with a mining machine, of a feed driving sprocket disposed on a horizontal axis extending longitudinally of the machine and rotatable in a transverse plane at the front end of the machine, a flexible feed chain, cooperating guiding means adjacent said sprocket, and cooperating forwardly located guiding sprockets rotatable on vertical axes and disposed at the opposite corners of the frame and in front of said driving sprocket.

46. The combination with a mining machine having horizontal kerf cutting mechanism, fast and slow feed mechanisms on the front end thereof, a horizontally disposed shaft extending in front of said mechanisms, means for selectively connecting the same to said feed mechanisms, and a feed sprocket on said shaft adapted to engage a feed chain and rotatable in a vertical plane.

47. The combination with a mining machine having horizontal kerf cutting mechanism, a plurality of transverse shafts, driving mechanism for one of the same, fast and slow feed mechanism between said shafts, a horizontal shaft on the front end of said machine, means operatively connecting the same to either feed mechanism, and a feed sprocket on said horizontal shaft and adapted to cooperate directly with a flexible feed member.

48. The combination with a mining machine having a frame slidable upon a surface thereof directly upon the mine bottom during cutting and horizontal-kerf cutting mechanism at the rear end of said frame, of feeding mechanism at the front end of the frame including a plurality of transverse shafts, fast and slow feed mechanism connected between the same, driving mechanism operatively connected to one of said shafts between the ends of the same, a horizontally disposed feed chain sprocket carrying shaft, and driving connections therefor between the ends of the other transverse shaft.

49. The combination with a mining machine having a frame slidable upon a surface thereof directly upon the mine bottom during cutting and horizontal-kerf cutting

mechanism at the rear end of the frame, of feeding mechanism at the front end of the frame, including a plurality of transverse shafts, fast and slow feed mechanism operatively connected between the same, a horizontally disposed shaft on the front end of said machine, means for selectively connecting the latter with either of said feed mechanisms, and a feed sprocket carried on said 10 horizontal shaft.

50. The combination with a mining machine, of feeding mechanism including a plurality of transverse shafts, fast and slow feed mechanism operatively connected between the opposite ends of the same, a horizontally disposed shaft extending longitudinally of the machine, means for selectively connecting it with either of said feed mechanisms, and a feed chain sprocket carried on said last mentioned shaft.

51. The combination with a mining machine having horizontal kerf cutting mechanism, of a longitudinally disposed motor, a transverse shaft, driving connections between said motor and shaft, a second transverse shaft, fast and slow feed connections between said shafts, a horizontally disposed feed chain sprocket driving shaft on the front end of the machine and operatively connected to said second transverse shaft, and a feed chain sprocket carried on said shaft.

52. The combination with a mining machine having horizontal kerf cutting mechanism including a pivoted cutter bar, of a motor, a transverse shaft, driving connections between said motor and shaft, a second transverse shaft, friction controlled fast and slow feed connections between said shafts, a horizontally disposed feed sprocket driving shaft operatively connected to said second transverse shaft, and a feed chain sprocket carried on said shaft.

53. The combination with a mining machine having a cutter bar pivoted on its rear end, of a longitudinally disposed motor, fast and slow speed transmission mechanism including a plurality of shafts, operative connections between said motor and one of said shafts, a feed operating member adapted to cooperate directly with flexible feeding means and rotatable on an axis extending longitudinally of the machine at the front end of said machine, and operative connections between said member and the other shaft.

54. The combination with a mining machine having a cutter bar pivoted on its rear end, a feed operating member adapted to cooperate directly with flexible feeding means and rotatable on an axis extending longitudinally of the machine on the front end of said machine, fast and slow speed driving mechanism for said member including a plurality of shafts, operative connec-

tions between said motor and one of said shafts, operative connections between said member and the other shaft, and means for reversing said feed operating member at will.

55. The combination with a mining machine, of a motor, a transverse shaft, worm and worm gear connections between the same, a second transverse shaft, friction controlled fast and slow feed driving mechanism between the opposite ends of said shafts, a horizontally disposed feed sprocket driving shaft disposed longitudinally of the machine, a feed sprocket on said feed sprocket driving shaft, and bevel gearing between said second shaft and said sprocket driving shaft.

56. The combination with a mining machine, of a motor, a transverse shaft, worm and worm gear connections between the same, a second transverse shaft, friction controlled fast and slow feed driving mechanism between the opposite ends of said shafts, a feed sprocket driving shaft disposed longitudinally of the machine, a feed sprocket on the front end of said feed sprocket driving shaft, bevel gearing between said second shaft and said sprocket driving shaft, and reversing mechanism operatively connected to certain of the elements of said bevel gearing.

57. The combination with a mining machine including a frame having a cutter bar projecting from one end thereof, of feeding means on said frame including a feed operating member adapted to cooperate directly with a flexible feeding member and rotatable on the opposite end of said frame on an axis extending longitudinally of the frame and cooperating guiding means including a guiding member disposed on an upright axis, said guiding member being so disposed at the edge of said machine as to receive a flexible feeding member operated on by said feed operating member and direct the same in either direction longitudinally of the machine frame.

58. The combination with a mining machine including a frame having a cutter projecting from one end thereof, of feeding means on said frame including a feed operating member adapted to cooperate directly with a flexible feeding member and rotatable on the opposite end of said frame on an axis extending longitudinally of the frame and cooperating guiding means including a plurality of guiding members disposed on upright axes, said guiding members being so disposed at the opposite edges of said machine as to receive a flexible feeding member operated on by said feed operating member and direct the same in either direction longitudinally of either side of the machine frame.

59. The combination with a mining ma-

chine including a frame having a cutter bar projecting from one end thereof, of feeding means on said frame including a feed operating member adapted to cooperate directly with a flexible feeding member and rotatable on the opposite end of said frame on an axis extending longitudinally of the frame and cooperating guiding means including a guiding member disposed on an upright axis, 10 said guiding member being so disposed at the edge of said machine as to receive a flexible feeding member operated on by said feed operating member and direct the same in either direction longitudinally of the machine frame, and a cooperating guiding member between said feed operating member and first mentioned guiding member adapted also to engage said flexible member.

60. The combination with a mining machine including a frame having a cutter bar projecting from one end thereof, of feeding means on said frame including a feed operating member adapted to cooperate directly with a flexible feeding member, and rotatable on the opposite end of said frame on an axis extending longitudinally of the frame and cooperating guiding means including a plurality of guiding members disposed on upright axes, said guiding members 25 being so disposed at the opposite edges of said machine as to receive a flexible feeding member operated on by said feed operating member and direct the same in either direction longitudinally of either side of the machine frame, and a plurality of cooperating 30 guiding members on opposite sides of said feed operating member and between the same and said first mentioned guiding members and adapted to engage and guide said 40 flexible member in passing from said feed operating member to said first mentioned guiding members.

61. The combination with a mining machine including a frame having a cutter bar 45 projecting from one end thereof, of feeding means on said frame including a feed operating member rotatable on the opposite end of said frame on an axis extending longitudinally of the frame, a flexible feeding member operated on by said feed operating member, and guiding means including a 50 plurality of guiding members rotatable on upright axes and adapted to direct said flexible feeding member longitudinally of said machine at different points spaced transversely from the longitudinal center line of the machine.

62. The combination with a mining machine including a frame having a cutter bar 60 projecting from one end thereof, of feeding means on said frame including a feed operating member rotatable on the opposite end of said frame on an axis extending longitudinally of the frame, a flexible feeding member operated on by said feed operating

member, and guiding means including a plurality of guiding members rotatable on upright axes and adapted to direct said flexible feeding member longitudinally of said machine in either direction at different 70 points spaced transversely from the longitudinal center line of the machine.

63. The combination with a mining machine including a frame having a cutter bar projecting from one end thereof, of feeding means on said frame including a feed operating member rotatable on the opposite end of said frame on an axis extending longitudinally of the frame, a flexible feeding member operated on by said feed operating member, and guiding means including a plurality of guiding members rotatable on upright axes and adapted to direct said flexible feeding member longitudinally of said machine in either direction at different points spaced transversely from the longitudinal center line of the machine, said guiding members including a guide member located 85 between said transversely spaced points.

64. The combination with a mining machine including a frame having a cutter bar projecting from one end thereof, of feeding means on said frame including a feed operating member rotatable on the opposite end of said frame on an axis extending longitudinally of the frame, a flexible feeding member operated on thereby, and cooperating guiding means including a plurality of guiding members rotatable on vertical axes and adapted to direct said flexible member longitudinally of said machine at different points spaced transversely from the longitudinal center line of the machine, said guiding members being so located as to permit reverse double transverse reeving of said flexible member when passing around different guiding members.

65. The combination with a mining machine including a frame having a cutter bar projecting from one end thereof, of feeding means on said frame including a motor and a feed operating member driven thereby and rotatable on the opposite end of said frame on an axis extending longitudinally of the frame, a flexible feeding member, and cooperating guiding means whereby said flexible member may cooperate with said feed operating member in reverse relations to effect lateral feeding of said frame in opposite directions during cutting.

66. The combination with a mining machine including a frame having a cutter bar projecting from one end thereof, of feeding means on said frame including a motor and a feed operating member driven thereby and rotatable on the opposite end of said frame on an axis extending longitudinally of the frame, a flexible feeding member, and cooperating guiding means whereby said flexible member may cooperate with said feed oper-

ating member in reverse relations to effect lateral feeding of said frame in either direction without reversal of said motor.

67. The combination with a mining machine including a frame having a cutter bar projecting from one end thereof, of feeding means on said frame including a motor and a feed operating member driven thereby and rotatable on the opposite end of said frame 10 on an axis extending longitudinally of the frame, a continuous flexible feeding member cooperating with said feed operating member and having a plurality of free ends, cooperating guiding means for said flexible member whereby the latter may be disposed in a plurality of feeding relations, and means whereby said feed operating member may be rotated at different speeds.

68. The combination with a mining machine including a frame having a cutter bar projecting from one end thereof, of feeding means on said frame including a motor and a feed operating member driven thereby and rotatable on the opposite end of said frame 25 on an axis extending longitudinally of the frame, a continuous flexible feeding member cooperating with said feed operating member and having a plurality of free ends, cooperating guiding means for said flexible member whereby the latter may be disposed in a plurality of feeding relations, and means whereby said feed operating member may be rotated at different speeds in opposite directions.

69. The combination with a mining machine including a frame having a cutter bar projecting from one end thereof, of feeding means on said frame including a motor and a feed operating member driven thereby and 40 rotatable on the opposite end of said frame on an axis extending longitudinally of the frame, a continuous flexible feeding member cooperating with said feed operating member and having a plurality of free ends, cooperating guiding means for said flexible member whereby the latter may be disposed in a plurality of feeding relations, and means whereby said feed operating member may be rotated at different speeds without reversing 45 said motor.

70. The combination with a mining machine including a frame having a cutter bar projecting from one end thereof, of feeding means on said frame including a motor and a feed operating member driven thereby and rotatable on the opposite end of said frame 55 on an axis extending longitudinally of the frame, a continuous flexible feeding member cooperating with said feed operating member and having a plurality of free ends, cooperating guiding means for said flexible member whereby the latter may be disposed in a plurality of feeding relations, and means whereby said feed operating member

may be rotated at different speeds in either 65 direction without reversing said motor.

71. The combination with a mining machine slideable over a mine bottom and having cutting mechanism including a cutter bar, flexible feeding mechanism for feeding 70 said machine laterally during cutting including a feed operating member rotatable on a horizontal axis, a cooperating flexible feeding member, means for driving said feed operating member at a cutting speed in 75 one direction, and means whereby the direction of feed of said machine may be selectively reversed including a reversible driving motor adapted to drive said feed operating member reversely, stationary guiding 80 means on said machine permitting reverse arrangement of said flexible feeding member without reversing the motor, and operative connections between said feed operating member and motor whereby without reversing 85 the motor the direction of rotation of said feed operating member may be reversed and the latter driven in either direction at like speeds.

72. In a mining machine, in combination, 90 a machine frame, cutting mechanism arranged at one end thereof, and feeding means therefor including a flexible feeding member and means on said frame adapted to cooperate with said flexible feeding member including a feed operating member adapted to operatively engage said flexible member during feeding and pairs of guide members arranged at opposite sides of said feed operating member and so positioned 95 that they are all tangent to a single straight line.

73. In a mining machine, in combination, 100 a machine frame, cutting mechanism arranged at one end thereof, and feeding means therefor including a flexible feeding member and means on said frame adapted to cooperate with said flexible feeding member including a feed operating member rotatable on an axis extending longitudinally 110 of the machine frame and adapted to operatively engage said flexible member during feeding, and pairs of idler guide members arranged at opposite sides of said feed operating member and rotatable on axes fixed 115 relative to the frame and at the end of the latter remote from said cutting mechanism and so positioned that lines tangent to the guide members of each pair will lie in a single plane.

74. In a mining machine, in combination, 120 a machine frame, cutting mechanism arranged at one end thereof, and feeding means therefor at the other end of said frame including a flexible feeding member 125 and means on said frame adapted to cooperate with said flexible feeding member including a feed operating member rotatable

on an axis extending longitudinally of the machine frame and adapted to operatively engage said flexible member during feed, and pairs of guide members arranged at opposite sides of said feed operating member and so positioned that lines respectively tangent to both the guide members of each pair will lie in a single vertical plane which cuts said feed operating member perpendicular to its axis of rotation.

75. In a mining machine, in combination, a machine frame, cutting mechanism arranged at one end thereof, and feeding means therefor including a flexible feeding member and means on said frame adapted to cooperate with said flexible feeding member including a feed operating member rotatable on a longitudinally extending horizontal axis adapted to operatively engage said flexible member during feeding, and pairs of guide members arranged at opposite sides of said feed operating member and so positioned that they are all tangent to a single straight line.

76. In a mining machine, in combination, a machine frame, cutting mechanism arranged at one end thereof, and feeding means therefor including a flexible feeding member and means on said frame adapted to cooperate with said flexible feeding member including a feed operating member rotatable on a longitudinally extending horizontal axis adapted to operatively engage said flexible member during feeding, and pairs of guide members arranged at opposite sides of said feed operating member and so positioned that lines tangent to the guide members of each pair will lie in a single plane.

77. In a mining machine, in combination, a machine frame, cutting mechanism arranged at one end thereof, and feeding means therefor including a flexible feeding member and means on said frame adapted to cooperate with said flexible feeding member including a feed operating member rotatable on a horizontal axis extending longitudinally of the machine frame and adapted to operatively engage said flexible member during feeding, and pairs of guide members arranged at opposite sides of said feed operating member and so positioned that lines tangent to the guide members of each pair will lie in a single plane which cuts said feed operating member perpendicular to its axis of rotation.

78. The combination with a mining machine slidable over a mine bottom and having cutting mechanism including a cutter bar, of flexible feeding mechanism for feeding said machine laterally during cutting including a feed operating member arranged at the opposite end of said machine from said cutting mechanism and rotatable on a horizontal axis extending longitudinally of the machine, a cooperating flexible

feeding member, means for at will driving said feed operating member at a cutting speed in one direction and at a uniform speed, and stationary guiding means on said machine permitting reverse arrangement of 70 said flexible feeding member relative to said feed operating member whereby said machine may be fed laterally during cutting at the same speed in opposite directions.

79. The combination with a mining machine slidable over a mine bottom and having cutting mechanism including a cutter bar, of flexible feeding mechanism for feeding said machine laterally during cutting including a single strand flexible feeding 80 member and a feed operating member arranged at the opposite end of said machine from said cutter bar and rotatable on a horizontal axis extending longitudinally of the machine, means for at will driving said feed operating member at a cutting speed in one direction, and guiding means on said machine permitting reverse arrangement of 85 said flexible feeding member relative to said feed operating member whereby said machine may be fed laterally during cutting at the same speed in opposite directions.

80. In a mining machine, in combination, a machine frame, cutting mechanism arranged at one end thereof, and feeding means therefor including a flexible feeding member and means on said frame adapted to cooperate with said flexible feeding member including a feed operating member rotatable on an axis extending longitudinally 95 of the machine frame and adapted operatively to engage said flexible member during feeding, and pairs of idler guiding members arranged at opposite sides of said feed operating member and rotatable on fixed axes 100 at the opposite end of said frame from said cutting mechanism.

81. In a mining machine, in combination, a machine frame, cutting mechanism arranged at one end thereof, and feeding means therefor including a flexible feeding member and means on said frame adapted to cooperate with said flexible feeding member including a feed operating member rotatable on an axis extending longitudinally of the 115 machine frame and adapted operatively to engage said flexible member during feeding, and pairs of guiding members arranged at opposite sides of said feed operating member and rotatable on fixed axes at the opposite end of said frame from said cutting mechanism and at the opposite side, with reference to said cutting mechanism, of a vertical transverse plane disposed at the 120 point of said feed operating member nearest to said cutting mechanism.

82. A mining machine slidable over a mine bottom on its bottom including a frame having at one end thereof a cutter bar having cutting mechanism associated therewith 130

and operative on actuation of the cutting mechanism associated therewith oppositely to cut and clear kerfs in opposite directions when the machine frame is oppositely propelled, and means for feeding said machine in opposite directions during cutting including a feed operating member adjacent the other end of said frame and rotatable upon a horizontal axis extending longitudinally of said frame, flexible feeding means cooperating therewith, and guiding members adapted to cooperate with said flexible feeding means and selectively operative dependent upon the direction of feed and arranged 10 on vertical axes at opposite sides of the end of said frame remote from said cutting mechanism.

83. A mining machine slidable over a mine bottom on its bottom including a frame having at one end thereof a cutter bar having cutting mechanism associated therewith and operative on reverse actuation of the cutting mechanism associated therewith to cut kerfs in opposite directions when the machine frame is oppositely propelled, and means for feeding said machine in opposite directions during cutting including a feed operating member adjacent the other end of said frame and rotatable upon a horizontal axis extending longitudinally of said frame, flexible feeding means cooperating therewith, and guiding means arranged in pairs at opposite sides of the central longitudinal vertical plane of said machine frame and at the end of the latter remote from said cutting mechanism.

84. A mining machine slidable over a mine bottom on its bottom including a frame having at one end thereof a cutter bar operative on reverse actuation of the cutting mechanism associated therewith to cut kerfs in opposite directions when the machine frame is oppositely propelled, and means for feeding said machine in opposite directions during cutting including a feed operating member rotatable upon a horizontal axis extending longitudinally of said frame and at the other end of said frame from said cutting mechanism, flexible feeding means cooperating with said member and towards one end of which said machine moves during cutting, and means for actuating said feed operating member at a plurality of speeds.

85. A mining machine slidable over a mine bottom on its bottom including a frame having at one end thereof a cutter bar operative on reverse actuation of the cutting mechanism associated therewith to cut kerfs in opposite directions when the machine frame is oppositely propelled, and means for feeding said machine in opposite directions during cutting including a feed operating member rotatable upon a horizontal axis extending longitudinally of said

frame and at the other end of said frame from said cutting mechanism, flexible feeding means cooperating with said member and towards one end of which said machine moves during cutting, and means for actuating said feed operating member at a plurality of speeds including a plurality of mutually coaxially arranged friction clutches.

86. A mining machine slidable over a mine bottom on its bottom including a frame having at one end thereof a cutter bar operative on reverse actuation of the cutting mechanism associated therewith to cut kerfs in opposite directions when the machine frame is oppositely propelled, and means for feeding said machine in opposite directions during cutting including a feed operating member rotatable upon a horizontal axis extending longitudinally of said frame and at the other end of said frame from said cutting mechanism, flexible feeding means cooperating with said member and towards one end of which said machine moves during cutting, and means for actuating said feed operating member at a plurality of speeds including a plurality of mutually coaxially arranged friction clutches one included in each of said feeds.

87. A mining apparatus comprising cutting mechanism, a frame supporting said cutting mechanism at one end thereof, a motor for driving said cutting mechanism having a power shaft having at one end thereof a driving element constituting a feed driving element, and means for effecting propulsion of said mining machine in a direction parallel to the major dimension of said frame including at the end of said frame opposite said cutting mechanism a power transmission member rotating on a horizontal axis extending longitudinally of the frame, and driving means for said member including a gear coaxial with said member and connected thereto for rotation at equal angular rates therewith and constituting a driving member therefor, and driving means for said gear operative to effect rotation thereof in opposite directions at different speeds including variable speed transmission mechanism driven by said motor all of whose elements between the driving element carried on the motor power shaft and the gear coaxial with said member rotate on parallel axes.

88. A mining apparatus comprising cutting mechanism, a frame supporting said cutting mechanism at one end thereof, a motor for driving said cutting mechanism having a power shaft having at one end thereof a driving element constituting a feed driving element, and means for effecting propulsion of said mining machine in a direction parallel to the major dimension of said frame including at the end of said frame opposite said cutting mechanism a power

transmission member rotating on a horizontal axis extending longitudinally of the frame, and driving means for said member including a gear coaxial with said member 5 and connected thereto for rotation at equal angular rates therewith and constituting a driving member therefor, and driving means for said gear operative to effect rotation thereof in opposite directions at different 10 speeds including variable speed transmission mechanism driven by said motor all of whose elements between the driving element carried on the motor power shaft and the gear coaxial with said member rotate on 15 parallel horizontal axes.

89. A mining apparatus comprising cutting mechanism, a frame supporting said cutting mechanism at one end thereof, a motor for driving said cutting mechanism 20 having a power shaft having at one end thereof a driving element constituting a feed driving element, and means for effecting propulsion of said mining machine in a direction parallel to the major dimension of 25 said frame including at the end of said frame opposite said cutting mechanism a power transmission member rotating on a horizontal axis extending longitudinally of the frame, and driving means for said member including a gear coaxial with said member and connected thereto for rotation at equal angular rates therewith and constituting a driving member therefor, and driving means for said gear operative to effect rotation 30 thereof in opposite directions at different speeds including variable speed transmission mechanism driven by said motor all of whose elements between the driving element carried on the motor power shaft and the gear coaxial with said member rotate on parallel horizontal axes. 35

40 and the gear coaxial with said member rotate on parallel axes, said variable speed transmission mechanism including coaxially disposed friction clutches selectively operative during drive at different speeds.

45 90. A mining apparatus comprising cutting mechanism, a frame supporting said cutting mechanism at one end thereof, a motor for driving said cutting mechanism having a power shaft having at one end 50 thereof a driving element constituting a feed driving element, and means for effecting propulsion of said mining machine in a direction parallel to the major dimension of said frame including at the end of said frame opposite said cutting mechanism a power transmission member rotating on a horizontal axis extending longitudinally of the frame, and driving means for said member including a gear coaxial with said member and connected thereto for rotation at 55 equal angular rates therewith and constituting a driving member therefor, and driving means for said gear operative to effect rotation thereof at different speeds including variable speed transmission mechanism driven by said motor all of whose elements between the driving element carried on the motor power shaft and the gear coaxial with said member rotate on parallel axes, said transmission mechanism including coaxially disposed friction clutches selectively operative 60 during drive at different speeds.

65 91. A mining apparatus comprising cutting mechanism, a frame supporting said cutting mechanism at one end thereof, a motor for driving said cutting mechanism having a power shaft having at one end 70 thereof a driving element constituting a feed driving element, and means for effecting propulsion of said mining machine in a direction parallel to the major dimension of said frame including at the end of said frame opposite said cutting mechanism a power transmission member rotating on a horizontal axis extending longitudinally of the frame, and driving means for said member including a gear coaxial with said member and connected thereto for rotation at equal angular rates therewith and constituting a driving member therefor, and driving means for said gear operative to effect rotation thereof in opposite directions at different speeds including variable speed transmission mechanism driven by said motor all of whose elements between the driving element carried on the motor power shaft and the gear coaxial with said member rotate on parallel axes.

75 92. A mining apparatus comprising cutting mechanism, a frame supporting said cutting mechanism at one end thereof, a motor for driving said cutting mechanism having a power shaft having at one end 80 thereof a driving element constituting a feed driving element, and means for effecting propulsion of said mining machine in a direction parallel to the major dimension of said frame including at the end of said frame opposite said cutting mechanism a power transmission member rotating on a horizontal axis extending longitudinally of the frame, and driving means for said member including a gear coaxial with said member and connected thereto for rotation at equal angular rates therewith and constituting a driving member therefor, and driving means for said gear operative to effect rotation thereof at different speeds including variable speed transmission mechanism driven by said motor all of whose elements between the driving element carried on the motor power shaft and the gear coaxial with said member rotate on parallel horizontal axes.

85 93. A mining apparatus comprising cutting mechanism, a frame supporting said cutting mechanism at one end thereof, a motor for driving said cutting mechanism having a power shaft having at one end 90 thereof a driving element constituting a feed driving element, and means for effecting propulsion of said mining machine in a direction parallel to the major dimension of said frame including at the end of said frame opposite said cutting mechanism a power transmission member rotating on a horizontal axis extending longitudinally of the frame, and driving means for said member including a gear coaxial with said member and connected thereto for rotation at equal angular rates therewith and constituting a driving member therefor, and driving means for said gear operative to effect rotation thereof at different speeds including variable speed transmission mechanism driven by said motor all of whose elements between the driving element carried on the motor power shaft and the gear coaxial with said member rotate on parallel axes, said transmission mechanism including coaxially disposed friction clutches selectively operative during drive at different speeds.

- rection parallel to the major dimension of said frame including at the end of said frame opposite said cutting mechanism a power transmission member adapted to 5 operate with a flexible feeding element and rotating on a horizontal axis extending longitudinally of the frame, and driving means for said member including a gear coaxial with said member and connected thereto for 10 rotation at equal angular rates therewith and constituting a driving member therefor, and driving means for said gear operative to effect rotation thereof in opposite directions including reversing transmission mechanism 15 driven by said motor all of whose elements between the driving element carried on the motor power shaft and the gear coaxial with said member rotate on parallel axes.
94. A mining apparatus comprising cutting mechanism, a frame supporting said cutting mechanism at one end thereof, a motor for driving said cutting mechanism having a power shaft having at one end thereof a driving element constituting a feed driv- 20 ing element, and means for effecting propulsion of said mining machine in a direction parallel to the major dimension of said frame including at the end of said frame opposite said cutting mechanism a power trans- 25 mission member rotating on a horizontal axis extending longitudinally of the frame, and driving means for said member including a gear coaxial with said member and connected thereto for rotation at equal angular rates 30 therewith and constituting a driving member therefor, and driving means for said gear operative to effect rotation thereof in opposite directions including reversing transmission mechanism driven by said motor all of 35 whose elements between the driving element carried on the motor power shaft and the gear coaxial with said member rotate on parallel horizontal axes.
95. A mining apparatus comprising cutting mechanism, a frame supporting said cutting mechanism at one end thereof, a motor for driving said cutting mechanism having a power shaft having at one end thereof a driving element constituting a feed driv- 45 ing element, and means for effecting propulsion of said mining machine in a direction parallel to the major dimension of said frame including at the end of said frame opposite said cutting mechanism a power transmission member adapted to 50 operate with a flexible feeding member and rotating on a horizontal axis extending longitudinally of the frame, and driving means for said member including a gear coaxial with said member and connected thereto for rotation at equal angular rates there- 55 with and constituting a driving member therefor, and driving means for said gear operative to effect rotation thereof in opposite directions including reversing transmission mechanism 60
96. Mining apparatus including a frame supporting at one end thereof cutting mechanism, and means for effecting propulsion of said apparatus during cutting in a path parallel to the major dimension of said frame including at the end of said frame remote from said cutting mechanism a driving member adapted to cooperate directly with flexible feeding means and rotatable upon a horizontal axis extending longitudinally of said frame, and driving means for said cutting mechanism and said member including a common motor disposed between said cutting mechanism and said member on said frame, the driving mechanism for said member including reversing gearing.
97. Mining apparatus including a frame supporting at one end thereof cutting mechanism, and means for effecting propulsion of said apparatus during cutting in a path parallel to the major dimension of said frame including at the end of said frame remote from said cutting mechanism a driving member adapted to cooperate directly with flexible feeding means and rotatable upon a horizontal axis extending longitudinally of said frame, and driving means for said cutting mechanism and said member including a common motor disposed between said cutting mechanism and said member on said frame, and having a power shaft parallel to the axis of rotation of said member, the driving mechanism for said member including reversing gearing.
98. A mining apparatus including a frame supporting at one end thereof cutting mechanism, and means for effecting propulsion of said apparatus during cutting in a path parallel to the major dimension of said frame including at the end of said frame remote from said cutting mechanism a driving member adapted to cooperate directly with flexible feeding means and rotatable upon a horizontal axis extending longitudinally of said frame, and driving means for said cutting mechanism and said member including a common motor disposed between said cutting mechanism and said member on said frame and having a power shaft whose axis lies in the same longitudinal vertical plane as the axis of said member, the driving mechanism for said member including reversing gearing.
99. Mining apparatus including a frame supporting at one end thereof cutting mechanism, and means for effecting propulsion of said apparatus during cutting in a path

parallel to the major dimension of said frame including at the end of the frame remote from the cutting mechanism a driving member adapted to cooperate directly with 5 flexible feeding means and rotatable upon a horizontal axis extending longitudinally of the frame, and driving means for the cutting mechanism and the member including a motor disposed between the cutting mechanism 10 and said member on the frame, the driving means for the member including mechanism operative to effect plural predetermined speed drive thereof.

100. Mining apparatus including a frame 15 supporting at one end thereof cutting mechanism, and means for effecting propulsion of said frame during cutting in a path parallel to the major dimension of said frame including at the end of said frame remote 20 from said cutting mechanism a driving member adapted to cooperate directly with flexible feeding means and rotatable upon a horizontal axis extending longitudinally of said frame, and driving means for said cutting mechanism and said member including 25 a motor disposed between said cutting mechanism and said member on said frame and having a power shaft parallel to the axis of rotation of said member, the driving means for the member including means for 30 effecting plural predetermined speed drive thereof.

101. A mining apparatus including a frame supporting at one end thereof cutting 35 mechanism, and means for effecting propulsion of said frame during cutting in a path parallel to the major dimension of said frame including at the end of said frame remote from said cutting mechanism a driving member adapted to cooperate directly with 40 flexible feeding means and rotatable upon a horizontal axis extending longitudinally of said frame, and driving means for said cutting mechanism and said member including 45 a motor disposed between said cutting mechanism and said member on said frame and having a power shaft whose axis lies in the same longitudinal vertical plane as the axis of said member, the driving means for the 50 member including gearing for effecting plural speed drive thereof.

102. Mining apparatus including a frame supporting at one end thereof cutting mechanism, and means for effecting propulsion 55 of said apparatus during cutting in a path parallel to the major dimension of said frame including at the end of said frame remote from said cutting mechanism a driving member adapted to cooperate directly 60 with flexible feeding means and rotatable upon a horizontal axis extending longitudinally of said frame, and driving means for said cutting mechanism and said member including a motor disposed between said 65 cutting mechanism and said member on said

frame, the driving means for said member including gearing for effecting drive thereof at different speeds in opposite directions.

103. Mining apparatus including a frame supporting at one end thereof cutting mechanism, and means for effecting propulsion of said frame during cutting in a path parallel to the major dimension of said frame including at the end of said frame remote from said cutting mechanism a driving 70 member adapted to cooperate directly with flexible feeding means and rotatable upon a horizontal axis extending longitudinally of said frame, and driving means for said cutting mechanism and said member including 75 a motor disposed between said cutting mechanism and said member on said frame and having a power shaft parallel to the axis of rotation of said member, the driving means for said member including gearing for effecting drive thereof at different speeds in 80 opposite directions.

104. A mining apparatus including a frame supporting at one end thereof cutting mechanism, and means for effecting propulsion of said frame during cutting in a path parallel to the major dimension of said frame including at the end of said frame remote from said cutting mechanism a driving member adapted to cooperate directly 90 with flexible feeding means and rotatable upon a horizontal axis extending longitudinally of said frame, and driving means for said cutting mechanism and said member including 95 a motor disposed between said cutting mechanism and said member on said frame and having a power shaft parallel to the axis of rotation of said member, the driving means for said member including gearing for effecting drive thereof at different speeds in 100 opposite directions.

105. In a mining machine, a machine frame slidable on its bottom directly on the mine bottom, a horizontal motor thereon having its axis extending longitudinally of the machine, cutting mechanism driven from one end of said motor, and feeding mechanism driven from the opposite end of said motor including a feed operating member 110 rotatable on a horizontal axis extending longitudinally of the machine and adapted to cooperate with flexible feeding means.

106. In a mining machine, a machine frame slidable on its bottom directly on the mine bottom, a horizontal motor thereon having its axis extending longitudinally of the machine, cutting mechanism driven from one end of said motor and including a horizontally swingable cutter bar, and feeding mechanism driven from the opposite end of said motor including a feed operating member rotatable on a horizontal axis extending longitudinally of the machine and adapted 120 to cooperate with flexible feeding means.

107. In a mining machine, a machine frame slideable on its bottom directly on the mine bottom, a motor thereon, cutting mechanism driven thereby, and feeding mechanism driven by said motor including a feed operating member adapted to cooperate with flexible feeding means, and plural speed driving mechanism between said motor and feed operating member including a horizontal worm, and a worm gear meshing therewith, and cooperating bevel gearing including a bevel gear rotatable on a horizontal axis extending transversely of the machine.
108. In a mining machine, a machine frame slideable on its bottom directly on the mine bottom, a motor thereon, cutting mechanism driven thereby, and feeding mechanism driven by said motor including a feed operating member adapted to cooperate with flexible feeding means, and plural speed driving mechanism between said motor and feed operating member including a horizontal worm and a worm gear meshing therewith, cooperating bevel gearing including a bevel gear rotatable on a horizontal axis extending transversely of the machine, and a bevel gear meshing with said gear rotating on a horizontal axis extending longitudinally of the machine.
109. In a mining machine, a machine frame slideable on its bottom directly on the mine bottom, a motor thereon, cutting mechanism driven thereby, and feeding mechanism driven by said motor including a feed operating member adapted to cooperate with flexible feeding means, and plural speed driving mechanism between said motor and feed operating member including a worm rotatable on a horizontal axis and a worm gear meshing therewith disposed on an axis at right angles to the axis of said feed operating member, and cooperating bevel

gearing including a bevel gear rotatable on a horizontal axis extending transversely of the machine.

45

110. In a mining machine, a machine frame slideable on its bottom directly on the mine bottom, a motor thereon, cutting mechanism driven thereby and feeding mechanism driven by said motor including a feed operating member adapted to cooperate with flexible feeding means, and plural speed driving mechanism between said motor and feed operating member including a worm rotatable on a horizontal axis and a worm gear meshing therewith disposed on an axis at right angles to the axis of said feed operating member, cooperating bevel gearing including a bevel gear rotatable on a horizontal axis extending transversely of the machine, and a bevel gear meshing with said gear rotating on a horizontal axis extending longitudinally of the machine.

50

111. In a mining machine, a frame slideable on its bottom on the mine bottom, a motor carried thereby, cutting mechanism driven by said motor including a cutter bar projecting from said frame at one end thereof, and feeding mechanism driven by said motor comprising a feed operating member rotatable on a horizontal axis extending longitudinally of the machine and located at the end of said frame opposite from said cutter bar, and flexible feeding means including a flexible feeding portion cooperating with said feed operating member and having its free end anchored at a point in advance of the machine, said feed operating member being adapted to draw in said flexible portion to advance said machine toward the anchor to extend its cut in the direction of said anchor.

CERTIFICATE OF CORRECTION

Patent No. 1,662,785.

Granted March 13, 1928, to

MORRIS P. HOLMES.

It is hereby certified that error appears in the printed specification of the above numbered patent requiring correction as follows: Page 8, line 8t, claim 44, for the word "blow" read "below"; page 10, line 24, claim 60, after the word "member" strike out the comma; and that the said Letters Patent should be read with these corrections therein that the same may conform to the record of the case in the Patent Office.

Signed and sealed this 3rd day of April, A. D. 1928.

Seal.

M. J. Moore,
Acting Commissioner of Patents.
